UNITED STATES PATENT OFFICE.

CLEVELAND O. YOUNG, OF CHICAGO, ILLINOIS.

STREET AND STATION INDICATOR.

1,108,652.

Specification of Letters Patent.

Patented Aug. 25, 1914.

Application filed July 9, 1913. Serial No. 778,031.

To all whom it may concern:

Be it known that I, CLEVELAND O. YOUNG, a citizen of the United States, residing at Chicago, in the county of Cook and State of Illinois, have invented certain new and useful Improvements in Street and Station Indicators, of which the following is a specification.

This invention relates to improvements in street and station indicators.

It has among others the following objects: to provide a street and station indicator that is electrically operated, wherein a web is used, having street names fixed thereon; the web being mounted on rolls, and means provided for operating said rolls; to provide means for sounding an alarm when certain names appear having instructions in connection therewith.

One embodiment of the invention is illustrated in the accompanying drawings, in which similar numerals refer to similar parts throughout the various views.

In the drawings—Figure 1 is a front elevation of the machine, showing a portion of the casing removed. Fig. 2 is an end elevation, having a portion of the casing removed. Fig. 3 is another end view of the invention, showing a portion of the casing removed. Fig. 4 is a vertical section on line 4—4 of Fig. 1. Fig. 5 is a top plan view of the operating mechanism. Figs. 6, 7 and 8 are details of the machine. Figs. 9 and 10 are partial mechanical and diagrammatical views showing one of the means that may be employed for operating the indicator and electrical circuits employed therewith. Fig. 11 is a detail view of the mechanism for operating the shutters. Fig. 12 is an elevation of a portion of the web upon which the street names are fixed.

Referring specifically to the drawings, 15 indicates a casing of any suitable construction, for containing the mechanism.

16 and 17 are partitions between which the rolls 18, 19 and 20 extend and have bearings.

22 is a web of suitable material, which bears the street names. Roll 19 is provided with teeth or projections 23 that engage holes 24 near the edges of web 22.

Rollers 18 and 20 are provided with small gears 25 and 26 respectively. Gear 25 engages a gear 27 which is rotatably mounted

on a fixed stud 28, and small gear 26 engages gear 29 and is rotatably mounted on a fixed stud 30. A spiral spring 31 is provided having one end secured to the fixed stud 28 and the other end to gear 27. Another spiral spring 32 is provided; being coiled opposite to spring 31 and is secured to the fixed stud 30 and gear 29.

A worm gear 33 is mounted on roller 19 and engages worm 34, that is fixed on shaft 35. The said shaft also carries a spur gear 36 and has a bearing in bracket 37. Spur gear 36 engages a gear 38 on either side of which ratchet teeth 39 and 40 are provided. The said gear 38 is mounted on a shaft 41 having ends secured in members 42 and 43. 70 Rotatably mounted on shaft 41 are the members 44 and 45 which are similar in construction and serve as pawls to engage the ratchet teeth 39 and 40. Only one member can engage the teeth at any time. Figs. 7 and 8 illustrate one of the members 44, and 46 indicates the engaging projection for the ratchet.

The coil springs 47 and 48 being oppositely wound, are provided as means for 80 producing tension when the members 44 and 45 are actuated. They are secured to shaft 41 and members 44 and 45 respectively. Both members 44 and 45 are provided with pins 49 that are designed to engage the 85 forked ends of a yoke member 50 that is pivotally connected to an armature 51; the latter being a portion of a solenoid 52.

A shifter 53 is provided with forked wedge shaped ends 54 and 55 respectively, 90 for engaging or disengaging either of the members 44 or 45, by producing a horizontal movement of member 53 through the means provided; a screw 56 and crank 57.

The numerals 58 and 59 respectively indicate shutters that are provided to shut off the view during the operation of changing a street name. The shutters are pivotally mounted at each end and two of their relative ends are provided with extending 100 pivot members, 60 and 61, which are fitted with meshing spur gears 62 and 63. Pivot 60 is also provided with a tension spring 64 that is secured to the same at one end and to gear 62 at the other end. An arm 65 is 105 also fixed to pivot 60 and from one end of said arm, a flexible cord 66 is continued around pulley 67 to a slideable member 68

having guides 69 and a lower projection 70. A slotted link 71 connects member 68 to arm 72, the latter being secured to the yoke 50 and the former having a pin extending through the slot. A guide arm 73 is provided to serve as a supporting guide for a latch 74 that is pivotally secured in bracket 75 and a spring 76 is provided to add tension to the latch 74.

10 77 is a magnifying glass fitted in the casting 15, at the sight opening.

Referring especially to Fig. 2, 78 indicates a solenoid and 79 its armature having a projecting pin 80. 81 is an air check cylinder 15 supported by a bracket 82 that is insulated from same and 83 is an ordinary electric bell. 84 is a compression spring on armature 79.

As means for operating the indicator I 20 provide a storage battery 85 and the switches 86 and 87 that are insulated from trolley pole 88. I also provide a contact arm 89 of suitable material, that is connected to the trolley wire 90. From arm 89 25 extends arm 89^a. The object of arms 89 and 89^a is to close the switches 86 and 87 respectively, when brought in contact; which operation will, in the former case complete the circuit from the storage battery through 30 wire 91 to solenoid 52 and return through wire 91^a. Wire 93 extends from the storage battery to switch 87 and continues to solenoid 78, and returns through a return wire 93^a. A wire 95 connects storage battery 35 to electric bell 83 and from bell 83 I extend a return line 96. The object of this is to produce an alarm after the solenoid 78 has attracted the armature and released it. The attraction of the armature produces a contact between projection 80 on armature 79 40 and wire 96 which sends a current through the bell and returns through wire 93^a. The bell will continue to ring until the connection is broken between projection 80 and wire 96. 45 The air cylinder 81 allows the armature 79 to be attracted easily and quickly; at the same time compressing spring 84 and retards its return to hold the connection between 80 and 96 for a specific length of time. 50 The bell rings only when a street is indicated, with special instructions in connection therewith as shown in Fig. 12. Hence the two switches 86 and 87 are both used only when certain streets are indicated. 55 The bell will not ring when street names appear as in Fig. 1.

The web 22 is wound on roll 18 and passes over roll 19 to roll 20 where the same is secured. Through the movement of roll 19, 60 that is actuated by the gear 33 and worm 34, the web is released from roll 18 and wound on roll 20 at proper times. In effecting this movement the spiral member 81 gradually tightens through the gear connections and spiral member 82 gradually re-

leases its tension which produces the winding up action of roll 20.

The worm 34 and gear 33 are actuated on the spring stroke or during the return of the member 44. The act of sending a current through the solenoid 52 attracts its armature which, being connected to the yoke 51, will operate the ratchet member 44 and turning movement of the latter will be effected and the spring 47 will be put under tension. When the circuit of the solenoid is broken the tension of the spring 47 will turn the gear 38, by reason of the engagement of the projection 46 on said member 44 with the teeth 39 on said gear, the turning movement of which gear transmits movement to the gear 36 which actuates the worm 34 and the gear 33 to move the web; and the spring stroke also returns the yoke 50 and armature 51 to their original positions. The arm 89 is so located that the movement formerly described will take place at a point between two street intersections and at which time, the intersecting street ahead of the path of motion, will appear on the web, and be magnified by the glass 77.

I provide the shutter members 58 and 59 to obscure the web movement while a street name is being changed as described. The shutters are operated at the time of the attraction of armature 51.

Fig. 11 shows the position of the shutter operating mechanism at the end of the solenoid stroke, the member 68 being locked 100 and the shutters being closed. When the link 71 is moved to the left it carries with it the member 68 until the raised portion of the arm 73 causes the latch 74 to crowd between the lug 70 and the arm 73, the 105 flexibility of the latter permitting this action, so that the latch 74 will permit the lug 70 to pass and engage the same as shown in Fig. 11, which closes the shutters and extends the spring 64, the member 68 remaining locked until the solenoid releases its armature, permitting the link 71 to move to the right to a distance equal to the length of the slot therein, thereby shifting the arm 73 a sufficient distance to the right to withdraw its raised part from the latch 74, which latch 74 is then disengaged from the lug 70 by the spring 76, permitting the sliding member 68 to shift to the right and open the shutters, at or about the time the web is advanced by the pawl and spring mechanism described.

When the end of a car line is reached pawl 44 is thrown out of engagement by shifting the forked member 53 and member 45 is engaged. The indicator is then ready for a return trip and the web will be wound on roll 18 by a reverse movement of worm 34 and gear 33. The reverse movement is produced by the reverse action 130

of member 45 in relation to rotating gear 38, although member 45 is actuated in the same manner that 44 is actuated.

What I claim as new is:

5. 1. In a street and station indicator, the combination with an indicating web and means including a trip operated switch to advance the same, of a signal, and means to operate the same including a second trip 10 operated switch whereby the signal may be operated at selected operations of the web.

2. In a street and station indicator, the combination with an indicating web and means to intermittently advance the same, 15 a movable shutter adapted to conceal the indicating part of the web, and means to close the shutter while the web is being advanced, said means including a trolley contact and electrical devices operatively connected to the shutter.

3. In a street and station indicator, the combination with a double reel and indicating web operated thereby, of means to wind the web in either direction, said means including a roller over which the web passes, a wheel having opposite ratchets and geared to said roller, a pair of pawls engageable with the respective ratchets, an operating device engageable with either pawl, and 25 means to shift the pawls to engage one with and disengage the other from the corresponding ratchet and the operating device.

4. In a street and station indicator, the combination with a double reel and indicating web operated thereby, of means to wind the web in either direction, said means including a roller over which the web passes, a wheel having opposite ratchets and geared to said rollers, a pair of pawls engageable 30 with the respective ratchets, a shaft on which the pawls are slidale laterally, a shifter having wedge-shaped ends engageable with the pawls respectively to shift the same on the shaft and disengage either one 35 from the corresponding ratchet and operating device, and a spring pressing on each pawl and tending to shift the same to engagement.

5. In a street and station indicator, the combination with a double reel and indicating web operated thereby, of means to wind the web in either direction, said means including a roller over which the web passes, a wheel having opposite ratchets and geared to said roller, a pair of pawls engageable 50 with the respective ratchets, a contact operated solenoid and its armature, a yoke connected to the armature and the pawls, to operate the latter, and means to shift either pawl to disengage the same from the corresponding ratchet, a shutter adapted to conceal the indicating part of the web, and operating devices connected between the armature and the shutter to operate the latter when the former is operated. 60

6. In a street and station indicator, the combination with an indicating web and means including a trip operated switch to advance the same, of a signal, and means to operate the same including a second trip 15 operated switch whereby the signal may be operated at selected operations of the web and means to continue the operations of the signal for a certain period after its initial operation. 70

7. In a street and station indicator, the combination with an indicating web and means including a trip operated switch to advance the same, of a signal, and means to operate the same including a second trip 25 operated switch whereby the signal may be operated at selected operations of the web and means to continue the operation of the signal for a certain period after its initial operation said means including a solenoid 80 actuated by closing the last mentioned switch, and a dash pot connected to the armature of the solenoid to delay the return thereof after the switch is opened and the solenoid is deenergized. 85

In testimony whereof, I affix my signature in presence of two witnesses.
